UNITED STATES PATENT OFFICE.

JOHN L. CREVELING, OF NEW YORK, N. Y., ASSIGNOR, BY MESNE ASSIGNMENTS, TO
STANDARD HEAT AND VENTILATION COMPANY, INC., OF NEW YORK, N. Y., A
CORPORATION OF NEW YORK.

PRESSURE-REGULATOR.

1,098,616.

Specification of Letters Patent.

Patented June 2, 1914.

Application filed December 11, 1908. Serial No. 468,967.

To all whom it may concern:

Be it known that I, JOHN L. CREVELING, a resident of New York, in the county and State of New York, have invented a certain new and useful Improvement in Pressure-Regulators, as set forth in the annexed specification and drawing, forming a part thereof.

My invention has for its principal object 10 to produce means whereby the pressure upon the fluid delivered from a source of fluid pressure may be automatically regulated throughout various changes in pressure at said source and also throughout wide 15 changes in the amount of fluid delivered.

In the drawing I have shown one form 20 of pressure regulator embodying my invention and have chosen for illustration a type adapted to be placed on a locomotive and supply steam for heating a train drawn thereby. For this particular service the regulator is called upon to deliver a constant outlet pressure throughout reasonable 25 changes in the locomotive boiler pressure and throughout wide variations in the amount of steam necessary to heat the train, depending upon whether it may have one or many cars. Further, in this service it is 30 not only necessary that the regulator shall deliver a constant outlet pressure but shall also be adjustable so that low pressure steam may be delivered in fairly warm weather and fairly high pressure in extremely cold weather.

35 Figure I of the drawing represents a vertical section of my improved regulator and Fig. II a top plan of the main body portion thereof as may be readily understood from the following description.

40 In the drawing, (1) represents the body portion of the regulator provided with a threaded inlet (2) communicating with a high pressure chamber (3).

(4) represents a low pressure chamber 45 communicating with the threaded outlet (5).

The chambers (3) and (4) of the body portion (1) are connected by the screw threaded aperture (6) into which is screwed 50 a member (7) having a cylindrical opening therethrough indicated at (8) and carrying four members or webs (9) which form part of the cylindrical portion (10) which is

adapted to fit tightly into the cylindrical portion of the body (1) as indicated at (11). 55 The cylinder (10) is provided with an expanded portion (22) which is adapted to make a tight joint against the abutting surface of the body portion as indicated at (23).

(12) is a piston fitted closely to the cylinder (10) and may be provided with an extension (13) and piston rod (14) carrying the valve (15) adapted to seat against the member (7) as indicated at (16). The 65 valve (15) is provided with a grooved portion indicated at (17) and four extensions or guides as indicated at (18). The space between these extensions or guides terminates in V shaped openings indicated 70 at (19), the function of which will herein-after more plainly appear.

(20) represents a web or diaphragm portion at the end of cylinder (10) which may serve to hold the spring (21) tending to 75 press against the piston (12) in such manner as to hold the valve (15) against the seat (16) as shown in the drawing.

The bore of the cylinder (10) behind the piston (12) defines the cavity or chamber 80 (24) which is closed at the end as by the plug (25) provided with a cylindrical bore (26) closely fitting the plunger or extension (13) in such manner as to coöperate therewith to form a dash-pot.

85 The top of the body portion (1) which constitutes the main casing member is also provided with a circular flanged portion (27) having a central raised portion (28) upon which may be placed a light metallic 90 diaphragm (29) so as to define thereunder an annular cavity (30) communicating with the low pressure chamber (4) as by port (31).

95 The small port (32), the effective resistance of which may be regulated by the screw (33), communicates with the high pressure chamber (3) and the port (34) which registers with the port (35) of the cylinder portion (10) in such manner as to 100 communicate with the chamber (24) which is at the rear of the valve operating piston (12). The port (36) communicates with the port (34) and has one of its ends terminating against the diaphragm (29).

105 From an inspection of the drawings it

will be noted that the port 31 constitutes a by-pass or passage way which leads from the interior of the annular cavity 30 through the walls of the casing to the interior of the low pressure or outlet chamber 4. The ports 32, 34 and 35 are all located in the walls of the casing and extend along the same so as to provide a small passageway extending from the high pressure or inlet chamber 3 to the rear of the valve piston 12.

(37) represents the bonnet of the regulator, screwed upon the member (27) in such manner as to firmly hold the diaphragm (29) in place and form a pressure tight joint.

(38) is a circular disk placed upon the diaphragm (29) and arranged so as to be pressed downwardly against the same by the spring (39) in such manner as to tend to firmly hold the diaphragm against the end of the port (36) so as to tend to hold the same closed. The bonnet (37) is provided with a threaded portion (40) engaging the threaded member (41), revoluble as by the hand wheel (42) in such manner that the pressure exerted by the spring (39) upon the diaphragm (29) may be regulated thereby.

The small port (43) may be drilled through the valve (15), piston rod (14) and extension (13) and plugged up as by means of screw (44) if desired, for a purpose which will hereinafter more plainly appear.

(45) represents a small opening adapted to drain the cylindrical portion (10).

The practical operation of my improved pressure regulator is substantially as follows: If the inlet pipe be properly made up into the threaded portion (2) and the outlet pipe into the threaded portion (5) and high pressure steam admitted into the chamber (3), the same will tend to close the valve (15) firmly upon the seat (16) so as to prevent passage of steam through the opening (8) into the low pressure chamber (4), and some high pressure steam will also pass through port (32), port (34) and port (35) into chamber (24) back of the piston (12) and force the same forward against the action of spring (21) and the pressure against the smaller area of the valve (15) so as to open the valve (15) and allow steam to pass into the low pressure chamber (4) in a manner which will hereinafter be more fully explained. As soon as the required pressure, as may be determined by the spring (39), shall have been reached within the chamber (4) and within the chamber (30) communicating therewith through the port (31) the diaphragm (29) will be lifted so as to open the port (36) into the low pressure chamber (30).

The opening of the port (36) will tend to decrease the pressure in the chamber (24)

until the piston (12) takes such position that the valve (15) is in a proper position to give the required outlet pressure in the chamber (4) at which point the diaphragm will assume such position as to allow just enough steam to escape from the port (36) as will hold the required pressure in the chamber (24) to keep the valve in this position. Any decrease in the pressure in the outlet chamber (4) will allow the diaphragm to lessen the amount of steam bypassed through the port (36) and thus increase the pressure in the chamber (24) so as to cause the valve (15) to move forwardly so as to open more widely and compensate for such decrease in the chamber (4) while any increase in the chamber (4) will cause the diaphragm to more widely open the by-pass (36) and lessen the pressure in the chamber (24) so as to cause the valve (15) to move rearwardly so as to more nearly close, thus reducing the pressure in the chamber (4). In this way the regulator will tend to hold the pressure in the chamber (4) substantially constant regardless of the amount of steam delivered therefrom within reasonable limits for which the regulator is designed, and the pressure to be maintained in the chamber (4) may be determined by increasing or decreasing the pressure exerted on the upper side of the diaphragm by spring (39) as by screwing down the cap (41) or unscrewing the same by means of hand wheel (42).

The screw (33) may be adjusted so as to regulate the comparative areas of the ports (32) and (36) so that the ratio of the main port to the by-pass may be regulated as desired for the purpose of adjustment.

It will be noted that the type of regulator shown in the drawing is capable of giving a long travel to the valve which is done for the purpose of gradually increasing or decreasing the effective area of said valve. In the type shown in the drawing this is accomplished by the V shaped openings which together with the internal surface of the cylindrical opening (8) form what might be termed a secondary valve, back of the valve (15) and its seat (16), so that when the valve (15) is lifted from its seat, considerable travel may be given to the valve before the V shaped openings (19) have sufficiently passed the edge of the cylindrical opening (8) to have opened any appreciable effective outlet area at which time any wire-drawing will take place between the internal surface of the cylinder (8) and the edge of the V shaped openings (19) rather than against the seat (16) and valve (15) and thereby save the same from undue wear or cutting due to this cause. Further it will be obvious that as these V shaped openings widen by increase in travel of the valve a given amount of motion may

be caused to gradually increase the effective outlet area of the valve for a considerable range.

The function of the spring (21) is to cause the valve (15) to always tend to assume a certain position without regard to the balance of the pressure upon the front of the valve and the back of the piston (12) and for some uses is desirable, but under ordinary circumstances for locomotive work may be omitted.

The function of the dash-pot formed by the member (13) and cavity (36) is to cause the valve to operate less suddenly than it would without the same and under certain conditions to prevent chattering.

While the regulator shown in the drawing is designed for high inlet pressure to be reduced to comparatively low outlet pressure it may be useful at times to have the same readily adjustable for low inlet pressure to an outlet pressure not far different from that of the inlet and for this purpose I have shown the port (43) through the valve stem (14) into the chamber (24) so that if the screw plug (44) be withdrawn high pressure steam may pass directly through the valve stem and into the chamber (24) in which case high pressure steam will tend to enter the chamber (24) both through the port (43) and ports (32), (34) and (35), and to be relieved by the port (36) upon lifting of the diaphragm (29), or under certain conditions, the regulator may be more applicable if the screw (33) be caused to close the port (32) entirely, when all steam into the chamber (24) will pass through the port (43) and will be relieved through ports (35) and (34) and (36) upon raising of the diaphragm (29) as above described.

It will be noted that the valve, valve seat, piston and spring as in use are all within the one member and that the annular threaded portion (7) together with members (9), cylinder (10) with expanded portion (22), form one member or casting which together with the valve, piston rod, piston and spring may all be assembled as one unit which may be readily screwed into operative position within the body portion (1) or removed and replaced by another like unit with very little difficulty and without necessitating the opening of the piping. Further, all of the wearing parts of the regulator may thus be easily removed or replaced without disturbing the body portion (1) and the valve (15) may be readily ground upon its seat (16) with little difficulty and without wearing any portion of the regulator forming a permanent part of the piping system. It will also be obvious that removal of the plug (25) will allow one to operate the valve by hand to see if the same works freely, also to clean the

cylinder and the dash-pot and to ascertain whether or not steam flows clearly through the ports.

It will be obvious that this type of regulator shown contains no long small ports except the port (34) which may be straight and easily cleaned with a wire, also that the regulator contains no small pilot valves requiring careful adjustment and that each time a new diaphragm is placed within the regulator the same provides a new pilot valve, so to speak. Further, it will be obvious that there is no portion of this type of regulator which forms a part of the piping system which fails to drain in such manner as to prevent any possible damage from freezing.

I do not wish in any way to limit myself to the exact type of regulator shown in the accompanying drawing or described in detail in the specification above, as the purpose of the said drawing and detail description is to clearly set forth one type of regulator which embodies my invention and which is shown and described in sufficient detail to enable one skilled in the art to make and use the same, for it is obvious that regulators differing greatly from the above described and illustrated regulator may be made without departing from the spirit of my invention which is as set forth in the following claims, to wit:

1. A pressure regulator comprising a body portion having inlet and outlet portions, a removable valve seat and a valve, placed between said portions so as to form a governing means between the same, said members carrying therewith complete actuating means for actuating the said governing means.

2. In a pressure regulator having a body portion, the combination with means for dividing said body portion into a high pressure chamber and a low pressure chamber comprehending a valve, and a removable valve seat, of a removable cylinder united to said valve seat and valve actuating means within said cylinder.

3. A pressure regulator comprehending a body portion, means for dividing said body portion into a high pressure chamber and a low pressure chamber comprising a valve and a removable valve seat combined with valve actuating mechanism for actuating said valve comprehending a cylinder attached to the said removable valve seat.

4. A pressure regulator comprehending a body portion, means for dividing said body portion into a high pressure chamber and a low pressure chamber comprising a valve and a removable valve seat combined with valve actuating mechanism for actuating said valve comprehending a cylinder attached to the said removable valve seat and means for establishing communication be-

tween the high pressure chamber and said cylinder to operate said valve actuating mechanism.

5. A pressure regulator comprehending a body portion, means for dividing said body portion into a high pressure chamber and a low pressure chamber comprising a valve and a removable valve seat combined with valve actuating mechanism for actuating 10 said valve comprehending a cylinder at-

tached to the said removable valve seat, means for establishing communication between the high pressure chamber and said cylinder to operate said valve actuating mechanism and means for controlling the 15 passage of fluid therethrough.

JOHN L. CREVELING.
